UNITED STATES PATENT OFFICE.

JACOB R. SCOTT, OF BOSTON, MASSACHUSETTS, ASSIGNOR TO UNITED SHOE MACHINERY COMPANY, OF PATERSON, NEW JERSEY, A CORPORATION OF NEW JERSEY.

MACHINE FOR BUFFING ARTICLES OF LEATHER.

SPECIFICATION forming part of Letters Patent No. 699,248, dated May 6, 1902.

Original application filed January 14, 1901, Serial No. 43,193. Divided and this application filed July 24, 1901. Serial No. 69,572. (No model.)

To all whom it may concern:

Be it known that I, JACOB R. SCOTT, a citizen of the United States, residing at Boston, in the county of Suffolk and State of Massachusetts, have invented certain new and useful Improvements in Machines for Buffing Articles of Leather; and I do hereby declare the following to be a full, clear, and exact description of the invention, such as will enable others skilled in the art to which it appertains to make and use the same.

The present invention relates to machines for buffing articles of leather, and more particularly to an improved form of buffing-roll for use in such machines.

The object of my invention is to provide an improved form of buffing-roll suitable for use in buffing-machines, such as machines for buffing the soles and heels of boots and shoes or for buffing the rough and unfinished surfaces of boot and shoe counters or stiffeners and similar articles.

With these objects in view my invention consists in the devices and combinations of devices hereinafter described and claimed, the advantages of which will be obvious to those skilled in the art from the following description.

The novel features of my improved buffing-roll relate to the means for yieldingly supporting the covering of abrasive material to allow it to conform to the surface of the article brought into contact therewith, to the form of the covering, to the means for securing the covering to the roll, and to the construction of the roll. I desire to state in this connection that except as limited by the language of the claims I do not consider my invention as limited to a roll provided with all the features of novelty above referred to; but it may be embodied in a roll provided with one or more of such features. I also desire to state that the several features of novelty may be embodied in many different forms and that my invention is not limited to the particular form illustrated in the drawings accompanying this application. The construction illustrated in the drawings, however, embodies my invention in the best form at pres-

ent known to me when all of the features are embodied in a single roll.

Referring to the drawings, Figure 1 is a view showing a preferred form of my improved buffing-roll in longitudinal section, the driving-shaft therefor in elevation, and the bearings of the machine in which the roll is mounted in section. Fig. 2 is a view in side elevation of a modified form of buffing-roll, and Fig. 3 is an isometric view of the tubular abrasive covering.

In Fig. 1, 1 represents a buffing-roll composed of flexible material, such as rubber, and provided with a rigid metallic core 2, which extends nearly to the end of the roll. The covering 3, of abrasive material, is shown separately at Fig. 3 and consists of a sheet bent into tubular form, with its edges overlapped and permanently secured together by adhesive. In order to avoid a ridge at the overlapped edge, the edges are beveled off, as shown. This tube of abrasive material is slipped over the roll 1 and held thereon by bulging the roll to grip the inner surface of the tube. The roll is preferably bulged at its ends, whereby its surface is made concave longitudinally of the roll, and the covering of abrasive material bridges the concave surface, as shown. The abrasive covering is thus yieldingly supported and can conform to the curved or irregular surface of the sole of a shoe, an unfinished counter, or similar article brought into contact therewith. By bridging the concave surface of the roll the covering of abrasive material confines a body of air between itself and the roll, which forms a pneumatic cushion for the covering.

In leather-buffing machines as ordinarily constructed the roll has been cylindrical in form and the abrasive covering has been applied thereto by stretching a sheet of abrasive material around the roll and turning the meeting edges inward and clamping them within the roll. By this construction the surface of the roll is unyielding and can only touch the curved or irregular surface of an article brought into contact therewith at a single point. For this reason the buffing of the sole of a shoe or the curved or irregular

surface of an article of leather is rendered slow, and satisfactory results are difficult to produce. Moreover, the point at which the edges of the abrasive covering are turned inward forms a depression with a ridge at each side, so that the abrasive material is rapidly worn away at this point and the covering destroyed. By my improved buffing-roll these defects are obviated, the covering of abrasive material being mounted to yield to conform to the curved or irregular surface of the article held in contact therewith, whereby the entire surface of the article is rapidly and satisfactorily buffed, and the tubular abrasive covering presenting no ridges or depressions to cause one portion of the covering to be worn away faster than another.

I am aware that it has been proposed to support the abrasive covering of a buffing-roll by means of a pad of yielding material; but such rolls are defective in operation, since while the abrasive material is allowed to yield somewhat to conform to the surface of the article the pressure is not uniform over the surface of the article in contact with the roll. Moreover, the extent to which the abrasive covering is allowed to yield is comparatively small. By providing a pneumatic cushion the abrasive covering is allowed to yield sufficiently to conform to the irregular surface of the article and exerts a uniform pressure upon all points of the surface in contact with the roll.

The tubular coverings 3 can be made of the desired length, or these coverings can be made in the form of long tubes and the desired length for a roll cut off when required for use. The tubular coverings are made the exact diameter to fit the roll for which they are intended and can be packed in small compact pass for shipment or storing by being pressed flat. To allow the tubular covering to be more readily slipped over the roll, the roll and its rigid core are preferably made in two sections, as shown in Fig. 1, whereby the covering can be slipped over one section and the other section inserted into the open end of the tube.

The means for bulging the roll at its ends to grip the tubular covering consists of clamping-disks 4 at each end of the roll, which are arranged to bear against the ends of the roll and bulge it into the form shown in Fig. 1. The roll may be cylindrical in form, or the surface may be concave longitudinally thereof before the roll is bulged. The flexible material of the roll is preferably rubber and in order to prevent the roll bulging except at the ends is fixedly secured to the core 2, preferably by being molded thereon. Also the core 2, upon which the rubber is molded, is preferably provided with a shoulder 5. The clamping-disks 4 may be provided with overhanging flanges 6, between which and the roll the covering 3 is gripped, or these flanges 65 may be omitted and the bulging of the roll alone depended upon for holding the covering in position.

In Fig. 2 I have shown a slightly-modified form of roll in which the rigid core consists of a cylindrical sleeve 7, and the means for bulging the roll consist of bevel-faced disks 8, which do not extend beyond the periphery of the roll. It will be understood that other means may be employed for clamping the covering to the roll.

The construction which I prefer to use for actuating the clamping-disks to bulge the roll is illustrated in Fig. 1, in which it will be seen that the clamping-disks 4 are carried by rotatable sleeves 9 and 10, mounted in bearings in the upper portion of a machine-frame 11. Through these sleeves and through the buffing-roll extends a driving-shaft 12, having a splined connection with the sleeves and with the core of the roll, so that the sleeves and roll rotate with the shaft. At one end the shaft 12 is provided with a driving-pulley 13, the hub of which bears against the end of the sleeve 9, and at the other end the shaft 12 is provided with a nut 14, screwed thereon, which bears against the end of the sleeve 10 and serves as a means for forcing the sleeve 10 endwise of the shaft. By this construction it will be seen that the thrust of the nut 14 is taken by the hub of the pulley 13 and that by screwing up the nut the roll will be compressed between the clamping-disks 4. By unscrewing the nut 14 the shaft 12 can be removed, leaving the sleeves 9 and 10 in position in their bearings and allowing the buffing-roll to be removed. By arranging the sleeves 9 and 10 to remain in their bearings when the shaft 12 is removed the accumulation of dust or dirt or other foreign substances in the bearing is prevented.

The roll above described is especially designed for use in the machine for buffing the rough and irregular surfaces of unfinished boot or shoe counters or stiffeners disclosed in my pending application, Serial No. 43,193, filed January 14, 1901, of which this application is a division. It will be understood, however, that the roll above described is capable of use in machines for buffing the bottoms and heels of shoes and in many other forms of leather-buffing machines.

Having thus indicated the nature and scope of my invention and having specifically described the preferred embodiment thereof, I claim as new and desire to secure by Letters Patent—

1. A machine for buffing articles of leather, having, in combination, a flexible roll, a tubular covering of abrasive material, and means for bulging the ends of the roll to grip the tubular covering, substantially as described.

2. A machine for buffing articles of leather, having, in combination, a roll provided with a surface concave longitudinally of the roll and a covering of abrasive material supported thereon and bridging the concave surface, substantially as described.

3. A machine for buffing articles of leather, having, in combination, a roll consisting of a

plurality of sections and provided with a surface concave longitudinally of the roll, and a tubular covering of abrasive material supported thereon and bridging the concave surface, substantially as described.

4. A machine for buffing articles of leather, having, in combination, a flexible roll provided with a rigid core fixedly secured thereto, a tubular covering of abrasive material and clamping-disks bearing against the ends of the roll to bulge the roll at its ends to grip the tubular covering, substantially as described.

5. A machine for buffing articles of leather,

having, in combination, a flexible roll, a tubular covering of abrasive material, rotatable sleeves mounted in bearings at each end of the roll, clamping-disks carried by said sleeves arranged to bear against the ends of the roll to bulge the roll to grip the tubular covering, and a shaft passing through the sleeves and roll, substantially as described.

In testimony whereof I affix my signature in presence of two witnesses.

JACOB R. SCOTT.
